UNITED STATES PATENT OFFICE

2,435,406

TRUSS

Edgar E. Prance, Quitman, Ga.

Application January 18, 1946, Serial No. 642,073

2 Claims. (Cl. 128—96)

1

My present invention has for its object to provide an improvement in trusses for the treatment and relief of persons suffering from a rupture or hernia, and it comprises an abdominal pressure member made with right and left hand portions so connected at their lower ends that their upper ends may be adjusted laterally relatively to each other, and their point of connection drawn rearwardly under the crotch between the legs of the wearer for the dual purpose of providing an adequate support to this portion of the anatomy and also more firmly anchoring the apparatus for bearing against the point of rupture.

My invention also has for its object to provide a truss especially designed for the treatment and relief of so-called low ruptures in the groin.

Another object of my invention is to furnish an abdominal bearing member for a truss in which provision is made for the relative lateral adjustment of two members or connected sections which renders them particularly adaptable for adjustment to the bodies of men of different sizes and is especially serviceable for the treatment and relief of double hernias, i. e., where ruptures occur on opposite sides of the median line of the abdomen.

To these and other ends my invention embodies further additional improvements all as will be fully described in the accompanying specification, the novel features thereof being set forth in the appended claims.

In the drawings:

Figure 1 is a front view of a truss showing one embodiment of my invention.

Figure 2 is a side elevation thereof the device being shown in its normal position.

Figure 3 is also a front elevation showing the sections of the body member expanded laterally.

Figure 4 is a side elevation of the body member illustrating one of the positions the lower end of said member will assume when in use.

Figure 5 is a perspective view of the adjustable center fastening especially adapted for use in securing the various belts or straps in adjusted position.

Figure 6 is a perspective view of a buckle for use in securing the various belts or straps in adjusted position.

Similar reference numerals in the several figures indicate similar parts.

A breech occurring in the muscular walls of the lower abdomen resulting from accident or otherwise if unattended may quickly result in serious damage and require prompt treatment

2

either surgically or by the application of a truss fitted to the point of separation of the muscles in a manner proper to prevent the protrusion of the omentum and other structures contained in the peritoneum. To this end I have provided a structure which is adapted to be worn as a palliative measure during the period the patient is undergoing scientific treatment, or worn permanently when such treatment is not available, or as well as in the more severe cases in which the hernial sac is not replaceable. My structure is adapted for use in those cases generally classified as inguinal, femoral and umbilical hernias and is particularly serviceable in cases where double hernias occur, one at each side of the body.

In carrying out my invention I provide a body bearing member intended to fit tightly against the lower area of the body contiguous to the upper ends of the thighs, generally defined as the groin, and to engage between the latter in the area anatomically referred to as the crotch. This member is composed of right and left hand parts indicated by A and B, respectively. They are united at their lower ends by a flexible neck portion C above which their contiguous edges are shaped as shown in Fig. 1 to provide a space for the accommodation of the penis and scrotum. At their upper adjacent edges the parts A and B are united by an articulated connection which permits them to independently conform to the body movements of the wearer while holding them in their adjusted position.

As it is also a function of this member to control the spacing of the upper ends of the parts A and B I construct it of two clips a and b which are adjustable toward and from each other by spacing screws 1 and 2. Each clip is provided on its rear outer end with a hook a'—b' which engages beneath wire loops 3 and 4. The latter lie close to the outer faces of the members A and B and are secured by embedding their ends in said members in any approved manner during the operation of forming them. The latter becomes a special job in many instances according to the specifications required to fit the truss to individual requirements. On the outer upper corners of each part A and B similar loops 5 and 6 are located in slight depressions, as indicated in Figs. 1 and 2, and engaging with them are the buckles by means of which the waist band or belt 7 is secured. These buckles, illustrated particularly in Fig. 6, comprise a base plate 8 having a tilting belt gripper 9 on its outer face and at its forward edge a tongue which is curled

beneath the plate to form a hook adapted to engage with one of the loops 5 or 6.

The body member parts A and B are suitably constructed so that their upper portions are stiff while their lower portions increase in flexibility toward the connecting neck C which possesses a degree of flexibility that permits it to be drawn tightly into the crotch by the leg bands E and F. In practice the body member may conveniently be made of a comparatively thick sheet of rubber, as indicated in the side elevational views Figs. 2 and 4. Alternate layers of rubber and fabric vulcanized may also be used. However, it will be seen that whatever the form of the flexible member may be the building up of its upper portion to provide the usual pressure pads will increase the stiffness of that portion of the member. The forward ends of these bands or straps are provided with hooks e and f which engage loops e' f' located on the forward portions of the necks in such a position that these straps draw against the lowermost points or edges of the neck C. These straps extend divergently under the buttocks and thence upwardly, their free ends being attached in any suitable manner to the rear side portions of the waist band; hence it will be seen that the tension placed upon them will cause the flexible neck C and its more flexible extremity to be drawn tightly into engagement with the lowermost point of the wearer's abdomen.

The vertical length of the parts A and B is sufficient to cover the area in which the hernia has developed. In most cases this will be found to lie in the region of Poupart's ligament which is a strongly marked line on the front of a person's body where the abdominal muscles stop and the leg muscles begin which is the weak point in the abdominal wall and is made so by the fact that in males there is a canal for a cord leading therethrough from the seminal vesicles inside the abdomen which forms a potential opening. On the inner face of either the part A or B, or

on both as occasion may require, there is placed an enlargement G in the exact position required which will press against the spot on the abdomen where the line of cleavage between the muscles has occurred as a result of intra-abdominal pressure. The size of this enlargement will be determined and formed as required to prevent the extension of a loop of the intestines or omentum thus offering resistance to the displacement of the viscera.

What I claim and desire to protect by Letters Patent is:

1. A truss comprising a body member composed of separate right and left hand sections united at their lower ends and relatively adjustable laterally, said sections being rigid at their upper portions and increasing in flexibility toward their lower extremities, an adjustable connection between their upper ends, and body straps connected to said sections.

2. A truss comprising similar right and left hand sections rigid at their upper ends with increasing flexibility toward their lower ends where they are flexibly attached to each other, metal loops attached to the outer faces of the members, a waist belt having buckles provided with hooks engaging two of said loops and leg straps having hooks engaging other of said loops and arranged to deflect the connection between the sections in a direction transversely thereof.
